CIRCUIT BREAKER MECHANISM

Howard G. MacDonald, Murrysville, Pa., assignor
to Westinghouse Electric & Manufacturing
Company, East Pittsburgh, Pa., a corporation of
Pennsylvania

Application June 21, 1940, Serial No. 341,613

16 Claims. (Cl. 200—89)

The invention relates to circuit breakers of the type adapted for high speed reclosing operation. Circuit breakers of this type usually embody a non-trip-free tripping means arranged to initially trip the breaker without releasing the breaker from its operative relation or connection to the closing means thereby permitting the breaker to be reclosed instantly without waiting for a resetting or retrieving operation. The breaker also embodies a trip-free tripping means which is effective to trip the breaker free of the closing means if the fault is still present upon reclosure of the circuit. It is sometimes necessary to close the circuit breaker manually as, for example, during maintenance, or when the power operated closing means becomes inoperative, and for this purpose the circuit breaker is provided with a manually operable closing device.

For safety of both apparatus and operator it is important that the circuit breaker should always be under the control of the trip-free tripping means whenever the breaker is being manually operated. To this end an object of the present invention is the provision of a circuit breaker of the class described with a means which is automatically effective to place the breaker under the control of the trip-free tripping means whenever the circuit breaker is being manually operated or manually closed.

The novel features that are considered characteristic of the invention are set forth in particular in the appended claims. The invention itself, however, both as to structure and operation together with additional objects and advantages thereof will be best understood from the following detailed description of one embodiment thereof when read in conjunction with the accompanying drawings, in which:

Figure 1 is a side elevational view, partly in section, of a circuit breaker operating mechanism embodying the features of the present invention, the mechanism being shown in the latched closed position with the closing solenoid deenergized;

Fig. 2 is a plan view of the circuit breaker operating mechanism shown in Fig. 1;

Fig. 3 is a fragmentary sectional view taken substantially along the line III—III of Fig. 2 showing the trip coil plunger and the rocking trip bar for operating either the trip free tripping latch or the non-trip-free tripping latch of the mechanism;

Fig. 4 is a partly schematic view of the operating mechanism and circuit breaker showing the relative position of the parts immediately 55

following a tripping operation by the non-trip-free latch;

Fig. 5 is a side elevational view of the operating mechanism in the open position with the manually operable closing device mounted in position for closing the breaker, the breaker being shown somewhat schematically as in Fig. 4;

Fig. 6 is a view similar to Fig. 5 except that it shows the mechanism at the beginning of a tripping operation after the breaker has been closed by the manual closing device;

Fig. 7 is a front elevational view, partly in section of the manually operable closing device; and

Fig. 8 is a side elevational view, partly in section, of the manually operable closing device.

The present invention is illustrated as applied to a circuit breaker operating mechanism of the type disclosed in Patent 2,150,587, issued to A. J. A. Peterson, March 14, 1939, and assigned to the assignee of the present invention. It is to be understood, however, that the principle of the invention is also applicable to any circuit breaker operating mechanism or system wherein tripping of the breaker in response to predetermined abnormal conditions is normally arranged to be effected by a non-trip-free tripping means so as to permit an instantaneous or high speed reclosure of the breaker, and wherein a trip free tripping means is also provided for effecting tripping of the breaker in response to the predetermined conditions at other times as, for example, when the fault is still present upon automatic reclosing of the breaker.

Referring to the drawings, the reference numeral 9 indicates generally a fabricated steel frame for supporting the various parts of the circuit breaker operating mechanism.

A closing solenoid 11 is mounted on the lower portion of the frame 9 and comprises a movable core 13, a cooperating stationary core 15 and an operating winding 17 which, when energized, pulls the movable core 13 downwardly to effect a closing operation of the circuit breaker.

A lever mechanism of the trip-free type indicated generally at 19 is mounted on the upper portion of the frame and this mechanism serves to normally connect the circuit breaker with the closing solenoid. The lever mechanism comprises a closing lever 21 which is pivoted at its right-hand end on the upper portion of the frame 9, and a breaker lever 23 which is pivoted at its left-hand end to the free end of the closing lever 21. The closing lever 21 consists of a pair of spaced parallel outer levers 25 (Fig.

2) which have their right-hand ends pivoted about a common axis by means of a pair of aligned pivot studs 27 carried by two spaced vertical plates 29 which form a part of the frame 9. The breaker lever 23 consists of a pair of spaced parallel inner levers 31 which have their left-hand ends pivoted on a pivot pin 33 carried by and connecting the free ends of the outer levers 25. The inner levers 31 which form the breaker lever are spaced so as to be movable into the space between the outer levers 25 which form the closing lever. The right-hand end of the breaker lever 23 carries a trip-free roller 35 which is mounted on a pin carried by and connecting the free ends of the inner lever 31.

The circuit breaker which may be of any suitable construction is shown schematically in Figs. 4 and 5 as comprising stationary main and arcing contacts 37 and 39 and a movable bridging contact assemblage 41 which consists of a laminated main bridging contact 43 for bridging the main stationary contacts 37, and a pair of spring biased movable arcing contacts 45 for engaging the stationary arcing contacts 39. The arcing contacts are arranged to engage prior to engagement of the main contacts during closing of the circuit breaker and to separate following separation of the main contacts during opening of the circuit breaker. The movable contact assemblage is carried by a rod 46 which is connected to the mid-portion of the breaker lever 23 through the agency of a pivoted lever 47 and an operating rod 49, the lower end of the operating rod 49 being pivotally connected to the breaker lever 23 by means of a pivot pin 51 which extends between the inner levers 31. The circuit breaker is biased to open circuit position by an opening spring 53.

The breaker lever 23 is biased upwardly by the opening bias of the circuit breaker, and the trip-free roller 35 carried by the free end of the lever 23 is normally engaged and releasably held in a position of alignment with the pivot axis 27 of the closing lever 21 by a trip-free latching mechanism indicated generally at 55 disposed adjacent the right hand end of the frame. When the trip-free roller 35 is held in latched position, the breaker lever 23 is operatively connected to the closing lever 21 for movement thereby. The closing lever 21 is connected to the movable core 13 of the closing solenoid 11 by means of a pair of connecting links 57, and the free end of the closing lever is adapted to be releasably held in closed position as shown in Fig. 1 by means of a non-trip free latch mechanism indicated generally at 59 disposed adjacent the left hand end of the frame and which engages a non-trip free roller 61 carried by the pivot pin 33.

The closing lever 21 is biased in a clockwise direction about its fixed pivot axis 27 by means of a pair of retrieving compression springs 63 which are disposed between each of the outer levers 25 and an upper supporting plate of the frame 9.

When the trip-free roller 35 carried by the free end of the breaker lever 23 is released by a releasing operation of the trip-free latch mechanism 55, the operative connection between the circuit breaker and the closing lever 21 is released and the breaker is moved to open circuit position under the influence of its opening spring free of any restraint by the closing means. The opening movement of the circuit breaker causes the breaker lever 23 to rotate in a counterclockwise direction toward the open position about

the pivot pin 33 which is held down by the non-trip free latch mechanism 59. The breaker lever 23 during a portion of its opening movement, effects an automatic releasing operation of the non-trip-free latching mechanism 59 to cause release of the free end of the closing lever 21. For this purpose the breaker lever 23 is provided with a projecting pin 65 adjacent its pivoted end which, during a portion of the opening movement of the lever 23 engages and rotates a pivoted bell crank releasing lever 67 to effect release of the non-trip-free latching mechanism 59 and consequently the free end of the closing lever 21. The bell crank releasing lever 67 is pivoted on a pivot pin 69 and is biased in counterclockwise direction by means of a coil spring 68 interposed between the upper supporting plate of the frame and a projection on the lever 67.

When the free end of the closing lever 21 is thus released by the releasing lever, the retrieving springs 63 rotate the closing lever 21 in a clockwise direction about its fixed pivot axis 27, and since the pivot pin 51 which connects the breaker operating rod 49 with the breaker lever 23 becomes stationary when the breaker reaches open position, the clockwise rotation of the closing lever 21 by the retrieving springs effects a clockwise rotation of the breaker lever 23 about the pivot pin 51 as a center to return the trip free roller 35 into latching engagement with the trip-free latch mechanism 55. At this point the two levers 21 and 23 are in the position shown in Fig. 4 and since the trip-free roller 35 is relatched by the trip-free latch mechanism 55, the breaker lever 23 is again operatively connected to the closing lever 21 and through the same to the movable core 13 of the closing solenoid.

When the closing solenoid 11 is energized, the two levers 21 and 23 are rotated in a counterclockwise direction about the common axis of the pivot studs 27 and the trip-free roller 35 to the closed position shown in Fig. 1 to effect closing of the circuit breaker. When the two levers reach the closed position the non-trip-free roller 61 carried by the pin 33 of the closing lever is reengaged and latched by the non-trip-free latch mechanism 59.

The circuit breaker may also be tripped open by a releasing operation of the non-trip-free latching mechanism 59. A releasing operation of the non-trip-free latch mechanism allows the circuit breaker to be moved to open position by its opening spring and this movement causes the two levers 21 and 23 to rotate in a clockwise direction about the common axis of the pivot studs 27 and the trip-free roller 35 to the open position shown in Fig. 4. In this instance, however, the circuit breaker remains operatively connected to the closing lever 21 and through the same to the movable core of the closing solenoid 11 so that the breaker can be immediately reclosed by energization of the closing solenoid 11.

The trip-free latch mechanism 55 (Fig. 1) comprises a main latch 69 pivoted on a pivot pin 71 carried by a part of the frame and is biased by means of a spring 73 to a latching position in which it engages and restrains the trip free roller 35 in the position shown in Fig. 1. A block 75 carried by the frame serves as a seat for one end of the latch spring 73, and this block is provided with a surface 77 which forms a stop to prevent movement of the latch 69 beyond its latching position. In order to hold the latch 69 in latching position against the upward bias exerted on the breaker lever 23, an auxiliary latch 79 is

provided. The latch 79 is pivoted by means of a pin 81 carried by a portion of the frame and is biased to latching position by means of a light spring 83. The nose of the latch 79 is provided with a substantially right angled notch 85 for engaging the upper corner of the main latch 69. The auxiliary latch 79 in latching position effectively locks the main latch 69 in its latching position. The auxiliary latch 79 is adapted to be moved in a clockwise direction about its pivot axis 81 to effect a releasing operation of the latch mechanism by a tripping means which will be hereinafter described.

When the auxiliary latch 79 is released, the trip-free roller 35 moves upwardly under the opening bias of the breaker forcing the main latch 69 in a clockwise direction until the roller 35 clears the nose of the latch. The spring 73 then returns the main latch 69 to latching position. The main latch 69 is provided with a rounded nose to allow the roller 35 to force the latch back and clear the same during resetting or retrieving of the breaker lever 23 and the roller 35. As soon as the trip-free roller 35 has cleared the nose of the latch 69 during a retrieving operation, the spring 73 returns the latch 69 to latching position and the auxiliary latch 79 returns to its latching position to engage and hold the main latch 69.

In order to ensure complete retrieving of the breaker lever 23 and the trip-free roller 35 to latching position, it is necessary that the auxiliary latch 79 be held in its released position free of the main latch 69 until the trip-free roller has been returned to its latching position. Otherwise the trip-free roller would jam against the rounded nose of the main latch 69 during a retrieving operation. For holding the auxiliary latch 79 in its released position during the release and retrieving of the breaker lever 23, there is provided a holding lever 87 pivoted on the pivot pin 81 and biased in a clockwise direction by a spring 89 which is slightly stronger than the latch spring 83. The lever 87 is provided with one extending arm 91 which lies in the path of the final retrieving movement of the free end of the breaker lever 23. When the trip-free roller 35 is in latching position, the free end of the breaker lever 23 holds the lever 87 down in an inoperative position to allow the auxiliary latch 79 to assume its latching position. However, when the trip-free roller moves upwardly following a tripping operation by the latch mechanism 55, the holding lever 87 rotates in a clockwise direction, and a cross pin 93 carried thereby engages and holds the auxiliary latch 79 in its released position until the trip-free roller has been retrieved to its latching position.

The non-trip-free latch mechanism 59 is substantially similar to the trip-free latch mechanism previously described. The latch mechanism 59 comprises a main latch 95 pivoted on the pin 97 carried by part of the frame, and the latch is biased by means of a spring 99 to latching position in which it engages and restrains the non-trip-free roller 61 carried by the closing lever 21. A block 101 carried by the frame serves as a support for one end of the spring 99, and this block is provided with a stop surface 103 (Fig. 4) for preventing movement of the latch 95 beyond its latching position. The main latch 95 is held in latching position by means of an auxiliary latch 105. The auxiliary latch 105 is pivoted on a pin 107 carried by a portion of the frame, and the latch 105 is biased to latching position by means

of a light spring 109. The nose of the latch 105 is provided with a substantially rectangular notch 111 for engaging the upper corner of the main latch 95 to lock the main latch in latching position, and the main latch 95 is provided with a rounded nose to permit it to be forced back and cleared by the non-trip-free roller 61 during closing movement of the closing lever 21. In order to permit the closing lever 21 to be moved to its completely closed position and to be relatched by the latch mechanism 59, there is provided a holding lever 113 which is similar to the holding lever 87 of the trip free latch mechanism 55. The holding lever 113 is pivoted on the pin 107 and is biased in a counterclockwise direction by a spring 115 which is slightly stronger than the latch spring 109. The lever 113 is provided with an arm 117 which extends into the path of the final closing movement of the free end of the closing lever 21. When the closing lever 21 is in the closed position shown in Fig. 1, the lever 113 is held down in an inoperative position to permit return of the auxiliary latch 105 to latching position. However, when the free end of the closing lever 21 moves upwardly following tripping operation of the latch member 105, the holding lever 113 rotates in a counterclockwise direction and a cross pin 120 carried thereby engages and holds the auxiliary latch 105 in released position clear of the main latch 95 until the closing lever 21 has been returned to the fully closed and latched position by the closing solenoid 11.

Both of the latching mechanisms 55 and 59 are adapted to be operated by a single trip coil 119 (Fig. 1). The trip coil 119 is mounted on a portion of the frame beneath the trip-free latch mechanism 55 and is provided with a trip plunger 121. The operating winding of the trip coil is adapted to be energized in response to predetermined overload conditions in the circuit controlled by the breaker or in response to any other abnormal condition under which tripping of the breaker is desired. Energization of the trip coil causes upward movement of the trip plunger 121. A rocking trip bar 123 (Fig. 3) rests freely on a plate 125 carried by the frame above the trip coil 119. The plate 125 is provided with an opening 127 for receiving the upper end of the trip plunger 121 and with suitable guides 129 for guiding the trip bar 123 and for preventing longitudinal and lateral displacement thereof. The trip plunger 121, when moved upwardly, engages the under side of the trip bar 123 to cause rocking movement of the bar about whichever end is held against movement. The auxiliary latch 79 of the trip-free latch mechanism 55 is disposed over one end of the trip bar 123 and the free end 131 of a pivoted bell crank lever 133 is disposed over the opposite end of the trip bar 123. The bell crank lever 133 is pivoted intermediate its ends on the pivot pin 81 carried by the frame 9, and the upper end of the bell crank lever is pivotally connected by means of a pivot pin 137 to the right-hand end of a horizontal connecting link 139. The left-hand end of the connecting link 139 engages the upper end of the releasing lever 67 through the agency of a pin and slot connection 141.

If the trip plunger 121 is moved upwardly at a time when the bell crank lever 133 is prevented from moving in a clockwise direction, the upward movement of the trip plunger 121 will cause the rocking trip bar 123 to rock about its end which engages the free end 131 of the bell crank lever 133 to effect upward movement of the aux-

iliary latch 79 to cause release of the trip free latch mechanism 55. On the other hand, if the trip plunger 121 is moved upwardly at a time when the auxiliary latch 79 is prevented from moving in a clockwise direction, the upward movement of the plunger 121 causes the rocking trip bar 123 to rock about its end which engages the auxiliary latch 79 to effect clockwise rotation of the bell crank lever 133. The clockwise rotation of the bell crank lever 133 moves the horizontal connecting link 139 towards the right and rotates the releasing lever 67 in a clockwise direction to effect release of the latch 105 and the non-trip free latch mechanism 59. If neither the bell crank lever 133 nor the auxiliary latch 79 are held against movement, the upward movement of the plunger 121 effects release of both the trip free and the non-trip free latch mechanisms.

In order to permit the circuit breaker to be automatically reclosed as quickly as possible following each initial opening operation caused by an overload or other abnormal condition, tripping of the breaker is normally arranged to be effected by the non-trip-free latch mechanism 59, providing the closing solenoid 11 is in deenergized condition and has been deenergized for a sufficient length of time for there to be no substantial magnetic flux present in the solenoid. When the breaker is tripped by the non-trip-free latch mechanism, it is moved to open position without releasing the operative connection between the breaker and the closing lever or solenoid so that the breaker can be quickly reclosed without waiting for any resetting or retrieving operation. This permits the circuit breaker to be reclosed in the shortest possible time. The closing solenoid may be arranged to be energized substantially simultaneously with the trip coil or during the initial portion of the opening movement of the breaker so that it will have developed sufficient flux to halt opening movement of the breaker and begin to reclose the breaker as soon as the arcs drawn between the contacts of the breaker have been extinguished, without allowing the breaker to continue to the full open circuit position. However, if the overload or abnormal condition occurs at a time when the solenoid is in an energized condition or when there is still an appreciable quantity of residual magnetic flux present in the solenoid, it is important that the breaker be tripped open by means of the trip-free latch mechanism 55 in order to permit high speed opening of the breaker unretarded by any opposing force or magnetic drag of the closing solenoid 11.

In order to provide for tripping of the breaker by the proper latch mechanism in accordance with the condition of the closing solenoid there is provided a means responsive directly to the magnetic flux of the closing solenoid for automatically selecting the proper latch mechanism 55 or 59 for operation by the trip coil 119. The automatic selecting means comprises a magnetic selector lever 145 which is pivoted intermediate its ends on the pivot pin 71. The lever 145 has a yoke-shape portion 147 of magnetic material which is disposed directly over the winding 17 and the magnetic frame of the closing solenoid 11 so as to be traversed and influenced by a portion of the magnetic flux of the solenoid. The selector lever 145 is biased in a clockwise direction to a normal unattracted position by means of a pair of springs 149 which are interposed between the yoke portion 147 of the lever and the

upper end plate of the solenoid 11. The right-hand arm 153 of the selector lever 145 is provided with an end or bar 155 which is disposed directly above the auxiliary latch member 79 of the trip-free latch mechanism 55.

When the solenoid 11 is deenergized and when there is substantially no magnetic flux present in the solenoid which would retard opening movement of the closing lever 21, the springs 149 maintain the selector lever 145 in the unattracted position shown in Figs. 1 and 4, in which position the projection 155 thereof engages and holds the auxiliary latch 79 of the trip-free latch mechanism 55 in latching position. The springs 149 are of sufficient strength to overcome the force of the trip plunger 121 and hold the auxiliary latch 79 in latching position to prevent operation of the trip-free latch mechanism 55 by the operation of the trip coil 119. If an overload condition occurs under these conditions, that is, with the magnetic selector lever in the unattracted position, the upward movement of the trip plunger 121 causes the trip bar 123 to be rocked about the end thereof engaged by the latch 79, to rotate the bell crank lever 133 in a clockwise direction. The clockwise rotation of the bell crank lever 133 moves the horizontal link 139 toward the right to cause clockwise rotation of the releasing lever 67 and consequently release of the non-trip-free latch mechanism 59. It will thus be seen that the occurrence of an overload when the selector lever 145 is in the unattracted position causes tripping of the breaker by means of the non-trip-free latch mechanism 59 only.

When the solenoid is in energized condition or whenever there is any appreciable magnetic flux present in the solenoid which would retard opening movement of the closing lever 21, the magnetic flux maintains the selector lever 145 in the attracted position shown in Fig. 5. In the attracted position of the magnetic selector lever 145, the projection 155 thereof is maintained in the raised position clear of the auxiliary latch 79 so as to permit operation of the trip-free latch mechanism 55. In its raised position the projection 155 engages a lug 157 carried by the horizontal link 139 to prevent right-hand movement of the link 139 and consequently clockwise movement of the bell crank lever 133. If an overload condition occurs under these conditions, that is, when the magnetic selector lever is in the attracted position due to the presence of magnetic flux in the solenoid 11, the upward movement of the trip plunger 121 will cause the trip bar 123 to rock about the end thereof which engages the arm 131 of the bell crank lever 133, to cause the trip bar to move the auxiliary latch 79 to released position since the bell crank lever 133 is prevented from being moved in a clockwise direction. Thus, the upward movement of the plunger 121 under these conditions effects a tripping operation of the breaker by means of the trip-free latch mechanism 55.

The pin and slot connection 141 between the left-hand end of the horizontal link 139 and the releasing lever 67 serves to allow the releasing lever 67 to be automatically moved to the released position during the upward movement of the breaker lever 23 to effect release of the closing lever and retrieving of the trip-free roller 35, even though the link 139 is prevented from being moved towards the right by the engagement of the projection 155 with the lug 157.

In order to prevent the magnetic selector lever from forcing the auxiliary latch 79 down to latch-

ing position in engagement with the main latch 69 at times when the trip-free roller 35 is away from latching position, the arm 153 of the lever 145 is provided with an interlock projection 159, which is adapted to be engaged by a short arm 161 of the holding lever 87 when the holding lever 87 is in the raised position, as shown in Fig. 5.

The circuit breaker and mechanism may be controlled by any suitable circuit breaker reclosing control system such, for example, as the system disclosed in Patent No. 2,150,584, issued to J. B. MacNeill, March 14, 1939, and assigned to the assignee of the present invention.

The circuit breaker operating mechanism as thus far described is of the same construction as disclosed in the aforementioned Patent No. 2,150,587 to A. J. A. Peterson.

It is sometimes necessary to close the circuit breaker by hand as, for example, during servicing or maintenance of the breaker or when the power operated closing means becomes inoperative for any reason. For this purpose the circuit breaker mechanism is provided with a manually operable closing device which is adapted to be removably mounted on the left-hand end of the circuit breaker operating mechanism as shown in Fig. 5 when it is desired to manually close the breaker. Referring to Figs. 5, 6, 7 and 8, the manually operable closing device consists of a jack of the screw type which when mounted on the circuit breaker mechanism engages a portion of the frame at one end and engages the movable end of the closing lever 21 at its other end. The construction of the manually operable closing device is best shown in Figs. 7 and 8, and the device comprises a housing or base 165 upon which is rotatably mounted a pair of parallel shafts 167 and 169. The shafts 167 and 169 are rotatably mounted at their lower ends in suitable bearings provided in the housing 165 and are retained in mounted position therein by collars fixed to the shafts above the housing and by fastening nuts 171 which thread onto the lower ends of the shafts, the fastening nuts 171 being retained in proper position by cotter pins 173. The shafts 167 and 169 are connected for simultaneous rotation together in the same direction by means of gears 175, 177 and 179 which are disposed within the hollow housing 165. The gear 175 is rigidly secured to the shaft 167 and engages the intermediate gear 177 which is rotatably mounted upon a centrally disposed stub shaft 181. The intermediate gear 177, in turn, meshes with the gear 179 which is rigidly secured to the shaft 169. The shafts 167 and 169 are braced at their upper ends by a cross bar 183 which is provided with bearing openings at each end for fitting over the upper reduced ends of the shafts 167 and 169, the shafts being free to rotate in the bearing openings. The cross bar 183 is retained in mounted position by retaining nuts 185 which are held in the proper position by cotter keys 187.

The upper portions of the shafts 167 and 169 are threaded in the same direction to provide worms 189, and mounted upon and threadedly engaging the worms 189 are a pair of traveling nuts 191. Each of the nuts 191 is provided with a pair of laterally projecting cylindrical lugs 193 which are adapted to engage in semi-cylindrical recesses 195 provided in the bifurcated ends 197 of the outer levers 25 of the closing lever 21, when the manually operable closing device is mounted in position on the circuit breaker operating mechanism.

The base 165 of the manually operable closing device is provided with a boss 199 intermediate the shafts 167 and 169 and this boss carries a cylindrical lug 201 which is retained in position by a setscrew 202. The ends of the lug 201 are adapted to seat in appropriate recesses 203 (Figs. 1, 2 and 5) provided in a pair of spaced plates 205 which form a part of the mechanism frame 9.

The traveling nuts 191 are prevented from 10 rotating with the shafts 167 and 169 by means of a pair of guide rods 207 which are secured at their upper ends to the cross bar 183 by means of nuts 208. The guide rods 207 extend through 15 openings provided in ears 214 which are formed integral with the nuts 191, and the lower ends of the rods 207 engaged in openings provided in washers 212 which are rotatably mounted on the shafts 167 and 169.

The shafts 167 and 169 which are geared for 20 simultaneous rotation together are rotated by means of an operating handle 213 which is adapted to drive the shaft 167 through the agency of a ratchet and pawl device. A ratchet wheel 215 is rigidly secured to the shaft 167 immediately above 25 the housing 165, and the operating handle 213 is provided with a hub 217 which is rotatably mounted on the shaft 167. The ratchet wheel 215 is nested within the hub 217 as shown in Fig. 7, and the hub 217 is provided with a reversible 30 pawl (not shown) which is adapted to engage in notches formed between teeth 219 of the ratchet wheel whereby the ratchet wheel and shaft 167 may be selectively rotated by the handle 213 in either direction.

35 If it is desired to manually close the circuit breaker, the manually operable closing device is mounted in position on the left-hand end of the circuit breaker operating mechanism as shown in Fig. 5 with the lug 201 seated in the recesses 203 40 of the frame 9 and the lugs 193 of the traveling nuts 191 seated in the semi-circular recesses 195 of the closing lever 21. To manually close the circuit breaker the operating handle 213 is manually rotated back and forth to effect progressive 45 rotation of the shaft 167, this movement being transmitted to the shaft 169 so that both of the shafts 167 and 169 are rotated together, and in a direction to cause downward movement of the nuts 191, thereby moving the closing lever 21 in a 50 counterclockwise or closing direction to effect closing of the breaker. The worm portions 189 of the shafts 167 and 169 are designed so as to be self-locking thereby permitting the breaker to be moved to any adjusted position and remain 55 in such a position without holding the operating handle 213. This permits the breaker to be serviced or adjusted by maintaining the contacts in any desired position.

As has previously been described, tripping of 60 the circuit breaker in response to an overload or other abnormal condition is normally arranged to be effected by the non-trip-free latching mechanism 59 in order to permit the breaker to be reclosed as quickly as possible on the first re-closure. For safety of both apparatus and operator, however, it is very important that the circuit breaker should be disposed for trip-free operation, that is, be capable of being opened in response to operation of the trip coil irrespective 65 of the position of the closing lever whenever the breaker is being operated by the manually operable closing device. Otherwise the breaker may be manually closed and held closed against a short circuit or fault condition. In accordance 70 with the invention, a device is provided which 75

is operable to automatically place the breaker under the control of a trip-free means or latching mechanism whenever the breaker is being manually operated by the manually operable closing device. In accordance with the embodiment of the invention illustrated, the device comprises a lever 209 which is pivotally mounted by a pivot pin 211 to the side of one of the vertical plates 205 of the mechanism frame 9. One end of the lever 209 extends to a position directly over a projection 210, on the magnetically responsive selector lever 145 (Figs. 1 and 2). An adjusting screw 216 is threaded through this longer end of the lever 209 and engages the projection 210 of the magnetically responsive selector lever 145. The other end of the interlock lever 209 projects downwardly alongside of the frame plate 205 and is disposed at the side of the notch 203 in a position to be engaged by one end of the cylindrical lug 201 of the manually operable closing device when the closing device is mounted in position on the circuit breaker mechanism. The adjusting screw 216 insures proper travel of the interlocking lever 209 so that when the manually operable closing device is mounted in position on the circuit breaker operating mechanism the lug 201 of the closing device causes the interlock lever 209 to move and hold the magnetic selector lever 145 in the attracted position, as shown in Figs. 5 and 6, thereby permitting the circuit breaker to be tripped by the trip-free latch mechanism 55 when the trip coil is energized. In other words, whenever the manually operable closing device is mounted in position on the circuit breaker mechanism for closing the breaker, the interlock lever 209 automatically places the breaker under the control of the trip-free latch mechanism 55 so that if the trip coil should be energized at this time or at any time when the manually operable closing device is being operated, the breaker will be tripped open irrespective of the position of the closing lever 21. Removal of the manually operable closing device leaves the magnetic selector lever 145 operative to select the proper latch in the manner previously described.

The operation of the circuit breaker and mechanism is briefly as follows. If an overload condition occurs when the mechanism is in the position shown in Fig. 1, that is, with the closing solenoid 11 deenergized and having no appreciable magnetic flux present therein, the upward movement of the trip plunger 121 by the operation of the trip coil 119 effects release of the non-trip-free latch mechanism 59 and the free end of the closing lever 21. Under these conditions the magnetic selector lever 145 is maintained in unattracted position by the springs 149 to prevent release of the trip-free latch mechanism 55. The breaker moves to open circuit position under the influence of its opening spring and the two levers 21 and 23 are rotated to the position shown in Fig. 4, the breaker remaining operatively connected to the movable core 13 of the closing solenoid. When the closing solenoid is energized to reclose the breaker, the two levers 21 and 23 are rotated in a counterclockwise direction about the common pivot axis of the studs 27 and the trip-free roller 35 which is held latched, to the closed position shown in Fig. 1 to effect closing of the circuit breaker. The energization of the closing solenoid to reclose the breaker also causes the magnetic selector lever 145 to be rotated to attracted position to free the trip-free latch mechanism 55 for operation by the trip coil 119, and

to prevent clockwise movement of the bell crank lever 133 by the trip coil 119. The magnetic selector lever 145 is maintained in attracted position by the magnetic flux after the solenoid 11 is deenergized until the residual magnetic flux has been reduced to substantially zero value. If the fault condition causing the overload is still present during reclosing of the breaker, when the arcing contacts engage, the trip coil 119 will again be energized and the trip plunger 121 moved upwardly; this time to effect release of the trip-free latch mechanism 55 and the trip-free roller 35 at about the moment the closing lever 21 reaches closed latched position. The release of the trip-free roller 35 immediately releases the operative connection between the breaker and the closing lever 21 and the circuit breaker moves to open circuit position under the influence of its opening spring free of any restraint by the closing means. The breaker lever 23 is moved in a counterclockwise direction about the pivot pin 33 and during a portion of its opening movement the projecting pin 65 engages and rotates the releasing lever 67 to effect release of the non-trip-free latch mechanism 59 and the free end of the closing lever 21 which has been brought to the closed and latched position by the closing operation. When the non-trip-free latch mechanism 59 and the closing lever 21 are released, the retrieving springs 63 rotate the closing lever in a clockwise direction about the fixed pivot axis 27 to return the trip-free roller 35 to latching position, where it is reengaged by the trip-free latch mechanism 55. The energization of the closing solenoid to reclose the circuit breaker after the trip-free roller has been relatched rotates both levers 21 and 23, together in a counterclockwise direction about the pivot axis 27 to the closed position to effect closing of the circuit breaker. If the fault condition causing the overload has in the meantime been cleared, the free end of the closing lever is moved to the fully closed position and is relatched by the non-trip-free latch mechanism 59 and the breaker remains closed.

When it is desired to manually close the circuit breaker the manually operable closing device is placed in position on the left-hand end of the circuit breaker operating mechanism as shown in Fig. 5 with the traveling lugs 133 seated in the notches provided in the closing lever 21 and the cylindrical lug 201 seated in the recesses 203 provided therefor in mechanism frame 9, and the operating handle 213 is manually rotated back and forth to effect manual closing of the circuit breaker in the manner previously described. It will be noted that whenever the manually operable closing device is mounted in position on the circuit breaker operating mechanism, the cylindrical lug 201 causes the interlock lever 209 to depress and hold the magnetic selector lever 145 in the attracted position irrespective of whether there is any magnetic flux present in the closing solenoid or not. With the magnetic selector lever 145 thus held in attracted position by interlock lever 209, the breaker is placed under the control of the trip-free latch mechanism 55 whenever the manually operable device is mounted in position on the operating mechanism and whenever the breaker is being manually operated by the manually operable closing device. As a result the circuit breaker will always be tripped free of the closing lever 21 if the trip coil should be operated at this time.

While the invention has been disclosed in accordance with the patent statutes, it is to be un-

derstood that various changes in the structural details thereof may be made without departing from the spirit of the invention. It is desired, therefore, that the appended claims be given the broadest reasonable interpretation permissible in the light of the prior art.

I claim as my invention:

1. In combination, a circuit breaker, power operated closing means for closing said breaker, a non-trip-free tripping means effective to trip said breaker in response to predetermined abnormal conditions at certain times, trip-free tripping means effective to trip said breaker in response to predetermined abnormal conditions at other times, manually operable means operable to cause closing of said breaker, and means operable to automatically place said breaker under the control of said trip-free tripping means whenever the breaker is being closed in response to operation of said manually operable means.

2. In combination a circuit breaker, power operated closing means for said breaker, a non-trip-free tripping means by which said breaker is tripped in response to predetermined abnormal conditions if said predetermined abnormal conditions occur at times when the breaker has been standing in one position for more than a predetermined length of time, trip-free tripping means by which said breaker is tripped free in response to predetermined abnormal conditions at other times, a manually operable closing device for closing said breaker, and means operable to automatically place said breaker under the control of said trip-free tripping means whenever the breaker is being operated by said manually operable closing device.

3. In combination, a circuit breaker, closing means movable to close said breaker, power operated means operable when energized to cause said closing means to close the breaker, a non-trip-free tripping means normally arranged to cause opening of the breaker in response to predetermined abnormal conditions in the circuit and leaving said breaker connected for closing by said closing means, trip-free tripping means operable in response to predetermined abnormal conditions to cause opening of the breaker irrespective of the position of the closing means, said trip-free tripping means being operable if said predetermined abnormal conditions occur when said power operated means is in energized condition, manually operable means operable to cause said closing means to close the breaker, and means operable to cause the breaker to be tripped free of the closing means if the predetermined abnormal conditions occur when the breaker is operated by said manually operable means.

4. In combination, a circuit breaker, closing means movable to close said breaker, power operated means operable when energized to cause said closing means to close the breaker, a non-trip-free tripping means normally arranged to cause opening of the breaker in response to predetermined abnormal conditions in the circuit and leaving said breaker connected for closing by said closing means, trip-free tripping means operable in response to predetermined abnormal conditions to cause opening of the breaker irrespective of the position of the closing means, said trip free tripping means being arranged to trip the breaker if the predetermined abnormal conditions occur within a predetermined length of time after a tripping operation by said non-trip-free tripping means, manually operable

means for operating the breaker, and means operable to automatically place said breaker under the control of said trip-free tripping means whenever the breaker is operated by said manually operable means.

5. In combination, a circuit breaker, power operated closing means for said breaker, tripping means for effecting opening of said breaker independently of the condition of said closing means, additional tripping means for effecting opening of said breaker only under certain conditions of said closing means, manually operable means for operating said breaker, and means operable to automatically place said breaker under the control of said first-mentioned tripping means when said breaker is operated by said manually operable means.

6. In combination, a circuit breaker, operating means movable to close said breaker, power operated means for causing said operating means to close the breaker, a non-trip-free tripping means normally arranged to cause opening of said breaker in response to predetermined abnormal conditions and leaving said breaker operatively connected for closing by said operating means, trip-free tripping means operable to cause opening of said breaker in response to predetermined abnormal conditions irrespective of the position of said operating means, said trip-free tripping means being effective to cause opening of the breaker if said predetermined abnormal conditions occur at times when said power operated means is applying a force opposing opening of the breaker, a manually operable closing device operable to cause said operating means to close said breaker, and means operable to automatically place said breaker under the control of said trip-free tripping means when said breaker is being operated by said manually operable device.

7. In combination, a circuit breaker, operating means movable to close the breaker, power operated means operable to cause said operating means to close the breaker, a non-trip-free tripping means operable to cause opening of said breaker in response to predetermined abnormal conditions if said predetermined abnormal conditions occur at times when said power operated means does not oppose opening of the breaker, said breaker remaining operatively connected for closing by said operating means when tripped by said non-trip-free tripping means, trip-free tripping means operable in response to predetermined abnormal conditions to cause opening of said breaker irrespective of the position of said operating means, said trip-free tripping means being arranged to cause opening of said breaker in response to said predetermined abnormal conditions if said predetermined abnormal conditions occur at times when said power operated means exerts a force opposing opening of the breaker, manually operable means for moving said operating means to operate the breaker, and means for causing said breaker to be tripped free of said operating means if said predetermined abnormal conditions occur at a time when said breaker is being operated by said manually operable means.

8. In combination, a circuit breaker, an operating member movable to close the breaker, electrically operated closing means operable to move said operating member to close the breaker, non-trip-free tripping means operable in response to predetermined abnormal conditions in the circuit to cause opening of said breaker only if said

closing means is deenergized, trip-free tripping means operable in response to predetermined abnormal conditions in the circuit to cause opening of the breaker irrespective of the position of the operating member and independently of the energized condition of the closing means, means responsive to the condition of the closing means for causing tripping of the breaker in response to said predetermined abnormal conditions to be effected only by said non-trip-free tripping means when said closing means is deenergized, and by said trip-free tripping means when said closing means is energized, manually operable means operable to move said operating member to operate the breaker, and means operable to cause tripping of the breaker in response to said predetermined abnormal conditions to be effected by said trip-free tripping means if said predetermined abnormal conditions occur when said breaker is operated by said manually operable device.

9. In combination, a circuit breaker, an operating member movable to close the breaker, electrically operated closing means operable to cause said operating member to close the breaker, non-trip-free tripping means operable in response to predetermined abnormal conditions in the circuit to cause opening of the breaker only if said closing means is deenergized, trip-free tripping means operable in response to predetermined abnormal conditions in the circuit to cause opening of the breaker irrespective of the position of said operating member and independently of the energized condition of said closing means, means responsive to the condition of said closing means for placing said breaker under the control of said non-trip-free tripping means only when said closing means is deenergized and under the control of said trip-free tripping means when the closing means is energized, a manually operable closing device operable to cause said operating member to close the breaker, and an element engageable by said manually operable closing device for automatically placing the breaker under the control of said trip-free tripping means when the breaker is being closed by said manually operable closing device.

10. In combination, a circuit breaker, an operating member movable to close the breaker, electromagnetic closing means for moving said operating member to close the breaker, non-trip-free tripping means operable in response to predetermined abnormal conditions in the circuit to cause opening of the breaker only if said electromagnetic means is in deenergized condition, trip-free tripping means operable in response to predetermined abnormal conditions in the circuit to cause opening of the breaker irrespective of the position of said operating member and independently of the energized condition of the closing means, an element responsive to the condition of said closing means for normally placing said breaker under the control of said non-trip-free tripping means only when said closing means is deenergized and under the control of said trip-free tripping means when said closing means is in energized condition, a manually operable device operable to move said operating member to close the breaker, and a member engageable by said manually operable device for causing said element to place said breaker under the control of said trip-free tripping means when said breaker is being operated by said manually operable device.

11. In combination, a circuit breaker, an oper-

ating member movable to close the breaker, power operated closing means for moving said operating member to close the breaker, non-trip-free tripping means operable in response to predetermined abnormal conditions in the circuit to cause opening of the breaker only if said closing means is deenergized, trip-free tripping means operable in response to predetermined abnormal conditions in the circuit to cause opening of the breaker irrespective of the position of said operating member and independently of the energized condition of said closing means, means operable to place said breaker under the control of said non-trip-free tripping means only when said closing means is in deenergized condition and under the control of said trip-free tripping means whenever said closing means exerts a force opposing opening of the breaker, a manually operable device operable to move said operating member to close the breaker, and means engageable by said manually operable device for automatically causing said breaker to be placed under the control of said trip-free tripping means whenever said breaker is being operated by said manually operable device.

12. In combination, a circuit breaker, an operating member movable to close the breaker, electromagnetic closing means for moving said operating member to close the breaker, non-trip-free tripping means operable in response to predetermined abnormal conditions in the circuit to cause opening of the breaker only when said closing means is in deenergized condition, trip-free tripping means operable in response to predetermined abnormal conditions in the circuit to cause opening of the breaker irrespective of the position of said operating member and independently of the energized condition of said closing means, means responsive to the magnetic flux of said closing means for normally placing the breaker under the control of said non-trip-free tripping means only when there is no substantial magnetic flux present in said closing means and for placing the breaker under the control of said trip-free means whenever there is any substantial magnetic flux present in said closing means, a manually operable closing device, and a member engageable by said manually operable closing device for automatically causing the breaker to be placed under the control of said trip-free tripping means whenever the breaker is being operated by said manually operable device.

13. In combination, a circuit breaker biased to open position, an operating member movable to close the breaker, power operated closing means operable to move said operating member to close the breaker, a first latch normally and releasably connecting the breaker to said operating member, said latch being releasable to cause opening of the breaker free of said operating member and closing means, a second latch for releasably holding said breaker closed, trip means operable in response to predetermined conditions for releasing said latches, means responsive to the condition of said closing means for causing said trip means to effect release of only said second latch if the predetermined conditions occur when said closing means is in deenergized condition and for causing said trip means to effect release of said first latch if the predetermined conditions occur when said closing means exerts any substantial force opposing opening of the breaker, a manually operable device operable to move said operating member to close the breaker, and means comprising a mem-

ber engageable by said manually operable device for automatically causing the operation of said trip means to effect release of the first latch if the predetermined conditions occur when the breaker is being operated by said manually operable device.

14. In combination, a circuit breaker biased to open position, an operating member movable to close the breaker, electromagnetic closing means operable to move said operating member to close the breaker, a first latch normally and releasably connecting said breaker to said operating member, said latch being releasable to cause opening of the breaker irrespective of the position of said operating member, a second latch for releasably holding the breaker closed, trip means operable in response to predetermined conditions for releasing said latches, a member responsive to the magnetic flux of said closing means operable to normally prevent release of said first latch by said trip means when there is no substantial magnetic flux in said closing means and operable to permit release of said first latch when there is any substantial magnetic flux in said closing means, a manually operable closing device operable to move said operating member to close the breaker, and means engageable by said manually operable device for automatically causing said magnetically responsive member to permit release of said first latch whenever the breaker is being operated by said manually operable device.

15. In combination, a circuit breaker, an operating member movable to close the breaker, clos-

ing means operable to move said operating member to close the breaker, a non-trip-free tripping means normally effective to cause opening of the breaker upon the occurrence of predetermined abnormal conditions, and a trip-free tripping means operable to cause opening of the breaker irrespective of the position of said operating member in response to predetermined abnormal conditions if said predetermined abnormal conditions occur at any time when a force is applied to said operating member opposing opening of the breaker.

16. In combination, a circuit breaker operating mechanism comprising an operating member movable to close the breaker, power operated means operable to move said operating member, non-trip-free tripping means effective to trip said breaker in response to predetermined abnormal conditions at certain times, trip-free tripping means effective in response to predetermined abnormal condition at other times to cause opening of the breaker irrespective of the position of said operating member, a manually operable closing device removably mountable on said operating mechanism for moving said operating member to close the breaker, and means operable to automatically place said breaker under the control of said trip-free tripping means whenever said manually operable closing device is in mounted position on said operating mechanism.

HOWARD G. MacDONALD.
